INCUBATOR FOR PREMATURE BABIES

Earnest L. Higginbotham, Hybla Valley, Va.

Application August 4, 1940, Serial No. 351,287

4 Claims. (Cl. 128—1)

This invention relates to incubators for use primarily in caring for premature babies.

For such use, an incubator should be so arranged as to produce conditions most favorable to the babies that are to be cared for in them. There are three vitally essential conditions that must be provided, these being; first, precise regulation of the temperature of the atmosphere that surrounds the baby; second, provision of a constant stream of fresh air, to insure a constant supply of fresh free oxygen; and third, regulation of the relative humidity of the air to maintain it sufficiently low to permit normal evaporation from the skin of the baby to regulate its temperature in normal fashion, and sufficiently high to prevent too rapid loss of moisture from the tissues by evaporation caused by too dry air.

Other conditions that are highly desirable are movement of the air within the incubating compartment at a speed sufficiently low to avoid turbulence or drafts, and maintenance of the air surrounding the baby's head at a temperature slightly lower than that surrounding the body, but avoiding sharp lines of demarcation between zones of different temperatures.

Additionally, such an incubator should be arranged for ready dismantling so that it can be easily and thoroughly cleaned and disinfected; and should provide for access to the interior while in operation with a minimum disturbance of the internal atmospheric conditions and a minimum direct communication with the outside atmosphere.

The chief object of the present invention is the provision, in an incubator for premature babies, of a novel air-supply system, whereby a constant, gently moving and non-turbulent stream of air is moved positively through the incubation compartment, and whereby the rate of flow of such stream of air is wholly independent of and unaffected by external conditions of temperature.

Another object is the provision in such an incubator of novel means for producing within the incubating compartment a relatively large region of substantially constant and uniform temperature, such region being substantially that in which the body of a baby is positioned, and a smaller region of a temperature a few degrees lower, for reception of the baby's head, and a graduated temperature region between the two regions first mentioned.

Still another object is to provide a novel heating and humidifying system for conditioning air to be supplied to the incubating chamber.

Another object is to provide an incubator for premature babies having a novel arrangement for supporting a baby, such arrangement permitting adjustment of the baby's position, and permitting ready removal of the supporting structure to permit thorough cleaning of the interior of the incubator.

A further object is to provide a novel and superior incubator for premature babies, that may be manufactured at low cost, and wherein all elements subject to wear or replacement may be readily and quickly obtained and installed.

A still further object is to provide in an incubator for premature babies a novel casing structure that permits full opening for access to the interior when the incubator is not in incubating use, and which also permits opening to a limited extent for access to the interior for ministrations to the needs of a baby within the incubating compartment with a minimum disturbance of the atmosphere within the incubating chamber.

In the accompanying drawings:

Figure 1 is a perspective view of an incubator constructed in accordance with the invention.

Figure 2 is a front elevation of the incubator with its front wall removed.

Figures 3 and 4 are sectional views on lines 3—3 and 4—4 respectively of Figure 2.

Figure 5 is a fragmentary perspective view of a portion of an end of the incubator.

Figure 6 is a fragmentary bottom plan view of the table support.

Figure 7 is an elevation of a specialized fan for use in the incubator.

Figure 8 is an end elevation of a specialized humidifier unit for use in the incubator.

Figure 9 is a plan view of such unit.

Figure 12 is a detail sectional view on line 12—12 of Figure 11.

Figures 13 and 14 are detail broken perspective views showing the door assembly in open and closed positions.

Figure 15 is a sectional view on line 15—15 of Figure 12.

Figure 16 is a sectional view on line 16—16 of Figure 12.

Figure 17 is a sectional view on line 17—17 of Figure 12.

Describing the drawings more particularly, the numeral 20 indicates generally a casing comprising a bottom wall 21, a lower vertical front wall 22, an inclined upper front wall 23, a rear wall

24, a top wall 25, a foot wall 26, and a head wall 27. With reference to the terms "head" and "foot," it is to be understood that they are used to indicate the respective end portions of the incubator within which the head and feet of a baby are intended to be placed, or the walls that close such respective ends.

The space enclosed by the casing 20 is longitudinally horizontally divided into a lower air conditioning chamber 28 and a superposed incubating compartment 29, by a horizontally disposed table support 30 that extends longitudinally between the head and foot walls. The support 30 is supported by transverse members 31 upon which the ends of the support 30 rest and which members 31 are respectively mounted on the end walls 26 and 27. The members are mounted by removable pins 30a that penetrate the members adjacent the front wall 22 and extend into sockets in the end walls, and pivot members 30b adjacent the rear wall 24. As it is often desirable to maintain a baby in an inclined position, the support 30 at each end is provided on its under side with an extensible pin 32 that may be engaged with any one of a series of vertically spaced sockets in the end walls 26 and 27. The pins 32 being centrally located on the support 30, when one end of the support is raised above its supporting member 31, the support 30 is maintained against transverse tipping by the engagement of the opposite end upon its supporting member 31.

The table support 30 is narrower than the distance between the side walls 22 and 24, and its edges are spaced from the inner surfaces of such walls, leaving longitudinally extending slots 35 that communicate between the chamber 28 and the incubating compartment 29, such slots extending continuously between the foot wall 26 and the head wall 27. Reticulated guards 36 are hinged and detachably secured to the upper surface of the support 30 adjacent its edges 34 by curved pins 37a that engage over a lower frame member 37 of the guards, the pins penetrating the reticulated guards above their lower frame members to provide pivotal mounting of the guards about their lower frame members. This arrangement permits the guards to be swung from an operative position guarding the slots 35 to an inoperative position, shown by the dotted lines, wherein the guards are collapsed on the surface of the support 30. The guards may be removed from the support 30 by sliding them off the pins 37a. When in operative position, the outer edges of the guards rest against the inner surfaces of the side walls 22 and 24 above the slots 35.

To furnish an accurately conditioned supply of air to the incubating compartment 29, the following system is provided. Adjacent the foot wall 26, and within the air-treating chamber 28, is a pair of air-heating devices, preferably light bulbs 38 secured in sockets 39, said devices being spaced apart transversely of the chamber 29 and located adjacent the side walls 22 and 24, and being mounted on the foot wall 26. Between the heaters 38, and adjacent the foot wall 26, is a specialized humidifying device 40.

As best shown in Figures 8 and 9, the humidifying device comprises a water tank 41 provided with a filling spout 42, which may be provided with a closure 43 hinged to the spout at one side of the opening and shown swung to its open position in Figure 8, and that extends through the foot wall 26. The tank 41 has a side wall 44 to

which is secured a laterally extending arcuate screen 45, the distal edge of which is secured to a supporting leg 46. An electric bulb 47, or other heating device, is arranged beneath the screen and between the wall 44 of the tank and the leg 46. The tank 41 is provided with a top wall 48 that is removably mounted on the tank as by hinging to one side wall thereof. The side wall 44 is, immediately above its juncture with the screen 45, provided with a slot 49, through which a cloth 50 extends into the tank. The cloth is spread over the upper surface of the screen 45. In operation, the cloth 50 is maintained moist by capillary attraction, and the moisture is evaporated by heat from the heater 47. Since, as will be later described, a definite volume of air per unit of time is moved over the surface of the cloth 50, and since the humidifying capacity of the device 40 is directly proportional to the area of cloth exposed to the air, the humidifying effect of the device can be adjusted by adjustment of the size of the area of cloth exposed.

The humidifying device 40 may be removably mounted by means of laterally extending fins 51 slidably engaged beneath flanges 51a that are secured to the bottom wall 26 of the casing.

To provide a continuous and regular flow of air through the incubating compartment 29 an air outlet 52 is provided in the head portion of the compartment, preferably in the head wall 27 adjacent its top. With the outlet 52 is associated an exhaust fan 53 driven by a synchronous electric motor of the kind commonly used in electric clocks. The assembly is best illustrated in Figure 7.

Referring to the wiring diagram, Figure 10, it will be seen that a common circuit, fed by the cord 54, Figure 2, includes the heaters 38 and the heater 47 in parallel, so that all are simultaneously operated when the circuit is energized. The humidifier heater 47 may be individually cut out by a manual switch 55. Simultaneous operation of the heaters 38 and 47 is controlled by a thermostatic switch 56. The motor of the fan 53 is connected across the circuit for constant operation independent of the switch 56, and may be separately controlled by a manual cut out switch 57. The circuit also includes an illuminating bulb 58 controlled by a manual switch 59.

Referring to Figures 2 and 4, it will be seen that the thermal-responsive element 60 of the thermostatic switch 56 is located in the foot portion of the incubating compartment 29, preferably being mounted on the foot wall 26. A manual control 61 for adjusting the operating temperature of the element 60 is arranged exteriorly of the wall 26. The thermostatic switch 56 is preferably of the micro-degree sensitive type that is commercially available.

The illuminating lamp 58 is conveniently located centrally of the incubating compartment 29 adjacent its top and mounted on the rear wall 24, the switch that controls it being operated by an external button 62. The fan motor cut out switch 57 may be operated by an external button 63.

In the foot wall 26 are provided air inlets 64, entering the air-treating chamber 28, and spaced as shown to distribute the air to the heaters 38 and humidifier 40. Air inlets 65 are provided in the head wall 27, such inlets also entering the chamber 28. Guard rods 66 are preferably arranged adjacent the inlets 65 of the head wall, for a purpose to be described later.

The operation of the apparatus so far described

will be readily understood. During actual operation of the incubator the fan operates continuously, and draws air from the incubating compartment at a constant rate sufficient to insure an ample supply of fresh air, yet sufficiently low to avoid drafts within the compartment 29. The rate of flow through the incubating compartment is unaffected by variations in external temperature conditions, which variations exert an effect upon the air flow in devices relying upon convection currents for circulation.

When the device is not in actual operation, it may be kept in idling condition, ready for instant use, by cutting out the operation of the fan while the heaters and humidifier are left in operation under control of the thermostatic switch. During such idling, the air within the incubating compartment 29 and air-conditioning chamber 28 will be kept at proper temperature and relative humidity with a minimum amount of operation of the conditioning devices 38 and 40, resulting in a minimum consumption of current. When the incubator is placed in service all that is necessary is to start the fan. The switch 57 is provided to enable this idling in readiness for instant use.

The organization of the air outlet 52 at the head of the incubating compartment 29, the heating and humidifying devices at the foot of the air-treating chamber 28, the air inlets 64 and 65 at the opposite ends of the latter chamber, and the longitudinal slots 35 extending the length of the interior of the incubator, all cooperate to provide the proper zones of variations in temperature within the incubating compartment. The arrangement of the heating and humidifying devices at the foot end of the air-treating chamber causes the air that enters by the inlets 64 to be treated, so that heated and moistened air is present in the foot portion of the chamber 28, while air at a lower temperature, having entered at a distance from the heaters and humidifier is present in the head end of the chamber. This latter air is heated to some extent by radiation from the heaters 38 and also by mixture with the heated air from the foot end of the chamber.

Since the exhaust fan 52 is located in the head end of the compartment 29, the air is drawn towards that end from both ends of the chamber 28, resulting in upward angular flow through the slots 35 throughout the length of the incubator. The distance between inlets 65 in the head wall 27 and the outlet 52 being appreciably less than the distance between the inlets 64 in the foot wall and the outlet, the cooler air that has entered the chamber 28 by the inlets 65 will tend to remain within a limited distance of the head wall 27, while the more highly heated and humidified air that entered by the foot inlets 64 traverses the entire length of the incubator and flows upward along various angular paths along the slots 35. These flows are indicated by the arrows in Figure 2. It will be seen from this figure that adjacent the foot wall 26 within the compartment 29 there is a relatively long zone wherein the air is almost exclusively that which has been subjected to the action of the treating devices 38 and 40, that adjacent this zone there is a short intermediate zone wherein the proportion of air that has entered by the head wall inlets 65 increases sharply, and that adjacent the head wall 27 there is a third zone, adjacent the upper surface of the table support 30 wherein the air is largely that which has entered by the inlets 65.

This zone arrangement permits the baby oc-

cupant's head to be surrounded by air that is several degrees cooler than that which surrounds his body, without there being a too sharp line of demarcation between the two zones, and without the necessity of partitioning the incubating compartment to maintain the two zones of different temperatures.

The simultaneous operation of the heating and humidifying devices affords an accurate control of the relative humidity. Relative humidity being a function of the temperature, when the humidifier is set in operation at the same instant that the heaters commence operating, the humidity is increased as the temperature is increased. The arrangement of the heating and humidifying devices in close proximity contributes to the uniform maintenance of the relative humidity. A relative humidity of from 55 to 65 per cent satisfies optimum conditions for the care of premature infants. By selecting the size of the exposed area of the cloth 50 with relation to the rate of air flow induced by the fan 53, the humidity can be readily maintained within these limits, and, except under external conditions of excessive humidity, when it is desirable to cut out the operation of the humidifier, the relative humidity within the incubating compartment will not be affected by external humidity conditions.

A door 67, that extends longitudinally the full length of the casing 20, is arranged in the lower vertical front wall 22, being hinged to the bottom wall 21 at 68, and spring latch devices 69 are arranged upon the end walls 26 and 27 for holding the door 66 in closed position. To remove the table support 30 from the incubator, the guards 36 are removed from the support, the pins 30a that support the front ends of the transverse members 31 are withdrawn, permitting the assembly of members 31 and support 30 to swing about the pivots 30b to the dotted line position of Figure 3, after which the support 30 may be slid from the members 31 through the door 67.

It is desirable in an incubator of this kind, particularly one that is readily portable, to provide for emergency use where electric current is not available. In the present incubator such emergency use can be accomplished by removing the heaters 38 and humidifier 40, and inserting bottles of water at the desired temperature into the chamber 28, by way of the door 67. The guards 66 arranged adjacent the inlets 65 in the head wall prevent the bottles from approaching the inlets sufficiently to interfere with the entry of air, the sockets 39 adjacent the foot wall serving the same purpose with relation to the inlets 64. This is of importance when the incubator is being moved about.

During use with heating by water bottles, air flow is accomplished by convection currents. By actual test it has been established that by using a number of one-quart standard "Mason" type jars filled with water at the desired temperature, and renewed at one hour intervals, the temperature of the incubating compartment is maintained sufficiently constant for practical use. It has also been found that there is sufficient evaporation from such jars provided with the usual packing rubbers and top screwed on handtight to maintain the humidity within satisfactory limits. While such use does not give the precise control of temperature and humidity that is achieved by using the electric system previously described, it does permit use where electricity is not available, and it permits transportation of the incubator while in actual, satisfactory op-

eration. It also is highly advantageous that the same incubator may be quickly and readily transferred from one type of operation to the other, as permitted by the arrangement just described.

In Figures 11 to 17 is disclosed a door assembly that is specially and peculiarly adapted for use in an incubator of this kind. The inclined upper front wall 23 comprises an upper longitudinal rail member 70 and a lower similar member 71, which members are vertically spaced apart. A pair of doors 72, that are slidable between the rails 70 and 71, are movable longitudinally of the casing from a closed relation with their adjacent edges in meeting relation to an open position to give access to the interior of the incubating compartment 29. The doors 72 are provided with observation panels 73 of shatterproof glass. Vertical handle slots 74 extend completely through the doors 72 adjacent their inner edges, for a purpose later to be described.

In order to provide an opening, smaller than that afforded by moving the doors 72 to their completely open relation and limited to a size just sufficient to permit access to the interior for necessary purposes while the incubator is in use, so that atmospheric conditions within the incubating chamber will be subjected to a minimum disturbance, an automatic guard assembly is organized with the doors 72.

Guard plates 75 are supported in face to face relation with the inside surfaces of the doors 72, the vertical extent of the plates being of such size as to cover the upper portion of the opening provided by the doors 72, and leaving below their lower edges only sufficient opening to permit access to the interior for performing such operations as are necessary.

The guard plates 75 are provided with spring latching means for releasably holding together their adjacent edges. Such means may advantageously be in the form of offsets 76 and 77 adjacent the meeting edges of the respective plates 75 and arranged to interengage to lock the plates together, and inclined portions 78 and 79 so arranged to permit the edges of the plates to override and spring into locking engagement when the plates are moved together. The plates 75 are supported by cover blocks 80 and 81 having ledges 82 that slidably engage the under edges of the plates 75. The blocks 80 and 81 are secured to the respective doors 72 as by screws 82a extending immediately above and below the lower edges of the plates 75. The edges of the plates 75 are provided towards their outer edges with extensions providing stops 83. When the doors 72 and the blocks 80 and 81 that are secured to them are moved in the directions towards their open positions, the guard plates 75 being in interlocked condition, the stops 83 engage with the screws 82 and thereby limit the opening movement of the doors to limit the longitudinal extent of the opening that is afforded, the vertical extent of such opening being limited by the guard plates.

The meeting edges of the cover blocks 80 and 81 are respectively provided with recesses 84 and 85 for the reception of the locking structures 76, 77, 78 and 79 when the doors are in closed positions. The recess 85 is bevelled off sufficiently to permit the marginal portion of the plate 75 with which the block 81 is associated, that portion including the innermost locking structure, to be moved inwardly of the casing to release the offset 76 from the offset 75 to disengage the locking engagement between the plates so that

they may move with the respective doors 72 to permit full opening of the incubator. A push button 86 extends through the door 72 behind which the movable structure 76 and 78 is located for effecting this release. Springs 87 may be interposed between the block 81 and its guard plate 75 to secure the interlocking engagement of the edges of the plates. Strips 88 are secured to the outer edges of the blocks 80 and 81 to engage the outer edges of the plates 75 as the doors are moved towards closed position and move the plates to interlocking position after they have been opened.

It will be noted from Figure 14 that the handle slots 74 of the doors 72, being open completely through the doors, expose areas of the guard plates 75. Suitable colored areas of the guard plates may be arranged to be exposed by the slots when the doors are in certain positions relative to the guard plates, to afford signals of such relative positions.

The closure assembly just described provides for automatic interlocking of the guard plates when the doors are moved to closed position, after which, opening of the doors results in the exposure of the opening that is limited to a size necessary for reaching into the incubating chamber for treating the occupant. When it is desirable to completely open the incubator, it is necessary to press the releasing button to disengage the guard plates, after which they move with the doors, permitting the doors to be moved to their fully open position and also open the guard plates. This arrangement effectively prevents accidental full opening of the incubator with an attendant disturbance of the internal atmospheric conditions.

From the foregoing the construction, operation and many advantages will be readily apparent to those skilled in the art, and it will be understood that changes in the size, shape, proportions and minor details may be resorted to without sacrificing any of the advantages of the invention or departing from the scope thereof as set forth in the appended claims.

I claim:

1. In an incubator for premature babies, said incubator including in superposed relation an incubating compartment and an air-supply chamber, means for supplying heated air to one end only of the air supply chamber and unheated air to the other end, and means for exhausting air from the end of the incubating compartment that corresponds to that to which unheated air is introduced to the air supply chamber; a horizontal partition extending longitudinally between the compartment and chamber and providing a table, said partition being so formed as to provide passage for air from the supply chamber to the incubating compartment at points between the ends of said chamber.

2. A horizontal partition according to claim 1, providing continuous longitudinal slots communicating between the compartment and chamber and extending substantially from end to end of said compartment.

3. A horizontal partition in accordance with claim 1, said partition being of less width than the chamber and compartment and having its edges spaced inward from the sides of the incubator, said partition being of sufficient width to provide a support for a baby.

4. A horizontal partition according to claim 1, said partition being of less width than the cham-

ber and compartment and having its edges spaced inward from the sides of the incubator, said partition being wide enough to support a baby on its surface within the incubating compartment, said partition being removably mounted between the compartment and chamber, and reticulated guards extending from end to end along the respective edges of the partition, said

guards being pivoted horizontally to the partition adjacent its edges, and said guards being of sufficient width to be swung into engagement with the walls of the incubator above the spaces between the edges of the partition and the walls of the incubator when the partition is mounted within the incubator.

EARNEST L. HIGGINBOTHAM.
